WILLIAM AITKEN, OF LIVERPOOL, ENGLAND.

TELEPHONE-EXCHANGE SYSTEM.

1,079,156.

Specification of Letters Patent.

Patented Nov. 18, 1913.

Application filed June 25, 1913. Serial No. 775,706.

To all whom it may concern:

Be it known that I, WILLIAM AITKEN, residing at Liverpool, England, have invented certain new and useful Improvements in 5 Telephone-Exchange Systems, of which the following is a specification.

My invention relates to telephone exchange systems and more particularly to an improved method of registering calls.

10 According to my invention there is provided in a telephone system, a substation meter which can be set so as to automatically limit the number of calls, which can be made, to a predetermined number.

15 The part of the meter which is set may be, or may form part of, a removable unit.

My invention enables a new method to be adopted in the method of paying for or renting of a telephone line.

20 In the system at present in general use, the subscriber pays an annual subscription or pays a certain sum for each call, sometimes beyond a certain number covered by a fixed sum, these methods being known as 25 flat rate and message rate systems of charging respectively. These methods involve a great amount of book-keeping and accounting by a large clerical staff, rendering of accounts, forwarding receipts for moneys paid and the provision of a staff for reading meters and for like purposes.

In the preferred method of carrying out 30 my invention, it is proposed to make the part of the meter which is set a removable unit or part of a removable unit as referred to above, and that these units should be made in a sealed form and sold at any telephone office or other suitable place. A party then desiring a telephone line 35 would pay preferably an installing charge and purchase a registering unit capable of registering such a number of calls as is convenient according to his requirements. When the unit is exhausted it would be replaced by a fresh one or each subscriber 40 might have two units, one to replace the other, the one not in use being taken to a telephone office and re-set for a fixed charge. The changing or fixing of the units would 45 be done in conjunction with an officer at the exchange to prevent fraud, preferably in a manner to be described.

My invention will be more fully understood from the following description taken

in connection with the accompanying drawings, in which:

Figure 1 illustrates, partly diagrammatically, a subscriber's instrument and meter. Fig. 2 shown on an enlarged scale and in detail the switch hook and a meter locking device. Figs. 3 and 4 illustrate means for giving a warning when a unit is nearly exhausted. Fig. 5 shows the essential parts of the cord circuit at the exchange and all the lines running to a called substation 65 with the battery reversing arrangements for automatic and manual exchange working, and Fig. 6 is a similar diagram to Fig. 5, the meter, however, being operated by differences in potential in a manual system. 70

Referring to Figs. 1 and 2 the substation comprises the usual receiver 1, transmitter 2, switch-hook 3, ringer 4 and condenser 5. The substation A also comprises a meter M. The general construction of the meter M is 75 of a well-known type and comprises a core 6 with an armature 7. The armature 7 has attached to it a pawl 8 which is adapted to engage the teeth of a ratchet wheel 9. This ratchet wheel is prevented from reverse rotation by a pawl 10. A spring 11 is connected at one end to the pawl 8 and at the other end to a fixed part 12, and keeps the pawl 8 in engagement with the ratchet wheel 9. A pin 13 prevents the pawl 8 85 dropping too far. Mounted on the spindle of the ratchet wheel 9 are the number disks 14 of the counting device. The core 6 is provided with two windings as shown, one winding 15 being of a large number of turns 90 and connected with the rods or terminals 16. The other winding 17 consists of a small number of turns and is connected at one end to one of the terminals 16 as shown and at the other end to contact 18. A spring 95 19 is connected to the lower of the two rods 16 as shown in the drawings and the arrangement is such that on the armature 7 being attracted, it presses the springs 19 against the contact 18, thereby putting the 100 winding 17 in parallel with the winding 15, so as not to diminish materially the current to the microphone. A condenser 20 is provided to shunt the inductive circuit and prevent sparking on breaking the circuit of the 105 winding 17. Instead of providing the winding 17 a wire might be arranged to short-circuit the coil 15 so as to allow the

full amount of current to pass to the microphone and thereby the condenser 20 might be dispensed with.

To the armature 7 is attached an extension 5 21 having pivoted to it a hinged barbed engaging arm 22. This arm 22 on the attraction of the armature 7 slips under the extension 23 (see Fig. 2) of the switch-hook 3 after the receiver is removed from the hook 10 and holds it so as to prevent flicking of the receiver hook at the called station from causing registration on the meter. The plate 24 is the front plate of the casing in which the meter is arranged and an opening is left 15 so that the portion of the meter inclosed within the casing 25 and the front plate 24 can be removed. The casing of the meter is provided at the back with a door 79, which is hinged at the bottom as shown, and has 20 a lock with seal over at its upper end whereby access may be had to the interior of the casing. The door also contains a hole through which the pawl 9 passes. The removable part of the meter therefore, consists 25 chiefly of the number wheels 14 and the ratchet wheel 9, the part 12 to which spring 11 is attached, being attached to the non-removable part. A window 26 fitted in the back of the casing is provided in front of 30 the number disks so that these can be read.

The front plate of the removable portion of the meter is provided at its four corners with pins. In Fig. 1, two of these are shown namely the pin 27 and the pin 28. Two 35 other pins 29 and 30 similar to 27 are provided at the other corners of the removable part. These pins are indicated in Fig. 3 and their purpose will hereinafter be fully described as also that of the pin 28. Beneath 40 the meter is arranged a locking magnet 31, consisting of a core having a winding 32 connected at one end to earth as shown and at the other end to a spring 33. Adjacent to the spring 33 are two springs 34 and 35. 45 The locking magnet 31 is provided with an armature 36 pivoted at 37 and having an upward extension 38 which is adapted to engage the spring 34. When the armature is attracted a pin 39 on the extension 38 is 50 adapted to engage the plate 40 to limit the upward extent of the movement of the extension 38.

Where the meter is operated by reversal of current in the line a permanent magnet 55 41 is provided which polarizes the core 6.

Means are provided for indicating to the subscriber and preferably to the operator the fact that no further calls can be made from the exchange owing to the meter having registered the number paid for and preferably also a signal should be given to the subscriber when the meter has registered a number of calls approaching the maximum number.

In Fig. 3 there is diagrammatically indicated a method of giving the signals just referred to, and in this figure there is also illustrated the use of the pins 27, 29 and 30 already referred to. The side of the line *a* is connected to the meter M, and through 70 the pin 27 to the spring 52. The other side of the line *b* is connected through the microphone 2, receiver 1 to the pin 29 which is connected to a spring 53 and to a spring 54. The pin 30 connects springs 55 and 56 to a 75 buzzer 57. The number wheel 14, shown in Fig. 3, carries a pin 58. When the pin reaches a position where it engages the spring 54 it closes this spring on to spring 55, thereby closing a circuit from the *b* side 80 of the line, through the buzzer, thus giving an indication that the calls paid for are nearly exhausted. On further rotation of the numeral wheel 14 the pin 58 engages the spring 53, moving this out of contact with 85 the spring 52 and thereby opening the circuit of the line and preventing any further calls being made until the meter is re-set or a new unit substituted therefor.

In Fig. 4, the arrangement just described 90 is shown in more elaboration. 59, 60, 61 and 62 are number wheels similar to the number wheels 14 already described. Contact pins 63 of insulating material are provided on each of these wheels and these contact pins 95 are adapted to force into contact four pairs of springs 64, 65, 66 and 67. The pins 63 may be so arranged that contacts are made between the respective pairs of springs 64, 65, 66 and 67 when the meter indicates a 100 number, for example, 9999. These springs are connected together as shown so that on the meter registering 9999, a circuit will be closed from the *b* line through the buzzer 57. The pairs of springs 64, 65, 66 and 67 are 105 placed within the incased removable portion of the meter and are connected by suitable wires passing out of the casing to the pins 27, 29 and 30, but for convenience in Fig. 1 the connections to these pins are not shown, 110 but the circuits are shown as if these pins were not employed. An additional wheel 68 may be provided carrying a pin 58 adapted to engage the pin 53 as described in connection with Fig. 3 to open the circuit of 115 the line while at the same time making contact with spring 56 and thereby closing a circuit through the buzzer 57. This buzzer therefore gives warning that the meter or unit is exhausted. A drop indicator may be 120 employed instead of a buzzer to give the warning signals, or to give one of the warning signals.

In Fig. 5 is shown the exchange circuit on an automatic or manual system in which the 125 battery is reversed when two subscribers are connected together. There is also shown a second substation A'. Figs. 1 and 5 taken

together show the connection between substation A and A'. In the cord circuit of a manual board (or the toll line board of an automatic system being controlled manually,) 5 a meter key 80 would be provided with a meter 81 to enable an operator to check the registering at the calling substation on a manual system and on both types of systems to check the additional registering for a 10 trunk line call. The meter for the latter purpose should preferably be of a type that returns automatically to normal after being disconnected from the circuit so that after the operator has asked the caller to move 15 the switch hook as many times as there are pence in the fee to be charged, she throws the meter 81 into circuit, when it would check the amount of the fee, the calling meter, however, only adding this number to 20 the previous total. The plugs of the cord circuit are indicated by dotted lines 82 and 83 being the tips, and 84 and 85 being the rings. The other details will be considered when describing the circuit.

25 In Fig. 6 a cord circuit is shown divided by a repeater instead of by condensers as in Fig. 5. The tips of the plugs are indicated by dotted lines at 120 and 121, the rings being indicated by dotted lines at 122 and 123, 30 the sleeves or test circuit being indicated at 124 and 125. The common battery is shown at B. Other details of the circuit will be described with the operating.

The operating of the system and the circuits are as follows: In an automatic system the calling dial indicated at 86 in Fig. 1 is provided with springs to short-circuit the meter if necessary, but as the calling current is not in the direction to operate the meter 40 this will not usually be necessary unless to reduce the resistance of the circuit. The receiver 1 will be lifted and the dial moved in the well-known manner. The circuit completed on lifting the receiver is from central 45 battery B, lower winding of relay 87, contact 88, contact 89, line b, transmitter 2, receiver 1, switch hook springs 91 and 90, springs 34 and 35, winding 15, line a, contacts 92 and 93, contacts 94 and 95, upper winding of relay 87, back to battery. The automatic functions that take place do not form part of my invention and the line is extended 50 through to the called station. When the receiver 96 is lifted a circuit is completed from central battery B lower winding of relay 97, 55 microphone 98, substation A', receiver 96, switch hook springs 99 and 100, upper winding of relay 97 to other side of battery B. Relay 97 is energized and completes a circuit from earth, winding of relay 101, contacts 102 and 103 of relay 97 to battery B. Relay 101 is energized and reverses the 60 connections of battery B to the a and b wires, the circuit being from battery B, through

lower winding of relay 87 contacts 104 and 65 94 of relay 101 to the a side of the line and then back over the b side of the line through contacts 89 and 105, upper winding of relay 87 to battery. The direction of current in the meter winding 15 is now of such a character as to strengthen the magnetism induced in the core by the permanent magnet 41, and the armature 7 is attracted to the core end. The receiver 1 is off the switch hook and when the pivoted barbed arm 22 70 strikes against the extension 23 of the switch hook it is deflected under it and the spring acting on the arm 22 causes the barbed head to engage with 23 so that the armature 7 cannot fall away when the winding 15 is 75 short-circuited by winding 17 on the closure of the contacts 18 and 19 or when the battery is reversed by the called receiver being replaced. When the armature 7 is first attracted, it, by means of the pawl 8, causes 80 the meter to register one call in a well-known manner. When the receiver is replaced the extension 23 is lifted and the armature 7 with the upright 21 and barbed arm 22 are free to fall away when the circuit is opened at the springs 90 and 91 of the switch hook. The condenser 20 is only required when winding 17 is used as a parallel circuit to the winding 15.

When the arrangement shown in Fig. 5 95 is used on a switchboard which is manually operated or on a toll board of an automatic system, the operator can check the registration of all calls, above the value of a normal local call, as for long junction and trunk 100 line connections. The call would be received on or be extended to an operator's position, where the toll lines could be connected. The operator after making the desired connection would insert the meter 81 105 by means of the key 80 the circuit then being from battery B by lower winding of relay 87, contacts 104 and 94, winding of meter 81, contacts 106 and 92 to wire A. The meter 81 may either record the total value of 110 the calls made or preferably only the value of the call about to be made and return to zero when disconnected from the circuit. The operator asks the caller to move the switch hook a number of times corresponding to the scale of charges and she would 115 check this by the reading on the meter. The meter key also completes a circuit from battery B, contacts 107 and 108 of key 80 through winding of relay 101 so that the 120 battery B is connected in the reverse direction whether the called station receiver is off or on the switch hook. Current for energizing the microphone is fed through the windings of relays 87 and 97, the circuit being divided for steady currents by condensers 109 and 110.

The operating and circuits shown in Fig.

6 are very similar to those shown and described in connection with Fig. 5.

When two lines have been connected together as described in connection with Figs. 5 1 and 6 the supervisory relays 126 and 127 are energized and the lamps 128 and 129 are shunted out by the resistances 130 and 131 which are brought into circuit by contacts 132 and 133, and 134 and 135 respectively. The lamp circuits are completed from battery B, resistances 136 and 137, lamps 128 and 129, sleeves of plugs 124 and 125, winding of cut-off relays 138 and 139 to earth respectively. When the operator 15 desires to register a call she brings the meter 140 into circuit by pressing key 141. This completes a circuit from battery B through battery B', meter 140, contacts 142 and 143 of key 141 to line b, through the instrument 20 shown in Fig. 1 and back to the a line, repeater winding 144 to the other side of the battery. The checking is as before described, but the meter at the calling station A has no permanent magnet 41 and the 25 meter is biased against the normal current from the battery B. As, however, this battery is now reinforced by battery B' the meters are energized that at the calling station recording the increased total, and the 30 operator's meter indicating the value of the present call corresponding to the number of times the operator presses the key. In this case the subscriber really checks the registering by the operator. The operator's telephone and the key for connecting it to the line are shown at 145 but form no part of my invention.

The subscriber utilizes the last number on the unit for obtaining the assistance of 40 an official at the exchange to replace the exhausted unit by a fresh one. The old unit will be withdrawn and at the same time current at a suitable voltage will be supplied to the b wire by the exchange official, the 45 circuit being from the b wire, contacts 34 and 33 of relay 31, winding 32 to earth. Relay 31 is energized and armature 36 attracted to the core end. Pin 38 is carried through the hole in the channel formed by 50 the plate 40 and lifts spring 34, the small projection 39 on the pin 38 preventing the latter from being raised sufficiently to allow the spring 34 to break contact with the spring 33. The tip of the spring 34 is however lifted sufficiently to allow of the pin 28 of the new unit, which pin is of an insulated beveled type engaging with the inside of pin 34 to cause it to break with contact 33 and make contact with spring 35. Should 55 the old unit be withdrawn and the exchange be not advised, the spring 34 would fall into the channel formed by the plate 40 and the pin 28 of a new unit inserted would pass over the tip of the spring 34 and

the line circuit would remain open at springs 65 34 and 35.

Though it is preferred to provide a replaceable unit as described, this need not be provided as other methods of setting the meter might be employed.

It is obvious that various other modifications might be made in the methods of carrying this invention into effect, those specifically described above being merely by way of example.

What I claim and desire to secure by Letters Patent is:—

1. In a telephone system, a subscriber's talking circuit, a call register and means controlled by said register for automatically 80 rendering said talking circuit inoperative when said register has been operated a predetermined number of times.

2. In a telephone system, a subscriber's talking circuit, a call register adapted to 85 register a predetermined number of calls, and means controlled by said register for rendering said talking circuit inoperative when all of said predetermined number of calls have been registered.

3. In a telephone system, a line, a call register adapted to register a predetermined number of calls, an electrically operated signal, means for operating said signal a short time before all of said calls are registered, 95 and automatic means controlled by said register for rendering said line inoperative when all of said calls are registered.

4. In a telephone system, a subscriber's talking circuit, a call register comprising an 100 electromagnet and a readily removable registering unit controlled by said electromagnet, said unit being adapted to register only a predetermined number of calls, and means whereby when said unit is removed said 105 talking circuit is rendered inoperative.

5. In a telephone system, a subscriber's talking circuit, a call register comprising an electromagnet and a removable registering unit controlled by said magnet, said unit being adapted to register only a predetermined number of calls, means for rendering said 110 talking circuit inoperative when all of said calls have been registered, and means for rendering the talking circuit inoperative 115 when said unit is removed.

6. In a telephone system, a subscriber's line, a call register including a removable registering unit, said unit being adapted to register only a predetermined number of 120 calls, and means for preventing said unit from being replaced after it has been removed.

7. In a telephone system, a subscriber's line, a call register including a removable 125 registering unit, said unit being adapted to register only a predetermined number of calls, an electromagnet connected with said

line, and locking means controlled by said last-mentioned electromagnet for preventing the unit, after it has been removed, from being replaced until said last-mentioned 5 electromagnet has been energized.

8. In a telephone system, a subscriber's talking circuit, a call register including an electromagnet and a registering unit controlled thereby and removable from the telephone system independently of the electromagnet, said unit being adapted to register 10 only a predetermined number of calls, a sub-

scriber's talking circuit partly carried by the removable unit, part of the unit being connected to the remaining part of the circuit by separable terminals, whereby when the unit is removed said talking circuit will be broken. 15

In testimony whereof I have affixed my signature in presence of two witnesses.

WILLIAM AITKEN.
